T. B. MORSE, OF NEW HAVEN, CONNECTICUT.

Letters Patent No. 79,494, dated June 30, 1868.

IMPROVEMENT IN CARRIAGE-SHACKLE.

The Schedule referred to in these Letters Patent and making part of the same.

TO ALL WHOM IT MAY CONCERN:

Be it known that I, T. B. MORSE, of New Haven, in the county of New Haven, and State of Connecticut, have invented a new Improvement in Carriage-Shackles; and I do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2 a top view,

Figure 3 a section on line xx ,

Figure 4 a perspective view of the block, detached,

Figure 5 a vertical central section, and in

Figure 6 the blank as heretofore used, introduced for the purpose of illustrating this improvement.

This invention relates to an improvement in what are known to the trade as "carriage-shackles," that is, the coupling or attachment for securing the shafts or pole to the axle of a carriage, the object being to construct the shackle so that a larger rubber packing may be inserted and secured than has heretofore been done, and without extra expense in construction.

The rubber packing heretofore used, and known as the "Chapman patent," is illustrated in fig. 6, A being the packing, B the thill-iron, and C the bolt. This packing has necessarily been thin back of the thill-iron head, as the blocks are constructed to be applied to shackles of common construction. The action of the raising and lowering of the thill-iron is illustrated in fig. 6. When the thill-iron is turned up, as denoted in the drawing, the rubber rolls down from the centre, as denoted in the drawing. On doubling the shaft to the position in red, the packing rolls up, as denoted in red, thus keeping a continual strain up and down upon the packing in the centre, which soon cracks and destroys the packing, so that it must be replaced by a new piece, the piece itself being simply a square block, made concave on one side, to fit the thill-iron head.

My invention, whereby this difficulty is overcome, consists in constructing the shackle with a deeper recess back of the thill-iron head, by forming a cavity in each internal angle of the shackle, the two edges of the shackle being supported by a web left in the shackle at the angles; also, in the construction of a block or packing, to correspond to the shackle so constructed.

In order to the clear understanding of my invention, I will fully describe the same as illustrated in the accompanying drawings.

D D are the two ears of the shackle, formed upon the clip E in the usual manner.

F is the thill-iron, fitted into the shackle in the usual manner, and secured by the bolt G.

The space back of the thill-iron head I cut away, so as to form a recess in each internal angle of the shackle, as denoted at a by the broken lines, figs. 2 and 3, leaving at the outer surface, above and below, in each of the said angles, a web for the support of the ears, as seen in fig. 2. This cavity may be formed by the process of forging, or may be cut out.

The block H is formed to correspond to the said recesses a , and, as clearly seen in fig. 4, the outer surfaces of the block corresponding in form to the edge of the web or braces in the angle of the shackle, and upon the rear of the block, at each corner, is formed a projection, corresponding to and so as to nearly or quite fill the said recesses a . The surface of the block next the thill-iron is made concave, to correspond to the head on the thill-iron. By this it will be seen that, as in vertical central section of the block, as in fig. 5, or a longitudinal section, as in fig. 3; the block for a shackle of the same size as heretofore constructed is nearly or quite doubled in thickness, therefore affording so much larger quantity of rubber at the centre, that the difficulty of cracking heretofore experienced in Chapman's rubber is entirely overcome. The extra thickness giving a greater amount of elasticity, the India-rubber block practically will last as long as the shackle itself.

The web in the angles also serves to hold the block in its place, so that it is not liable to drop out when the shafts are removed.

Having thus fully described my invention, what I claim as new and useful, and desire to secure by Letters Patent, is--

1. A shackle, constructed with the recesses α α in each of the internal angles, so as to receive the block H, substantially as and for the purpose specified.
2. The block H, formed from India rubber, and with projections d upon each angle, corresponding to the recesses α α in the shackle, substantially as and for the purpose specified.

T. B. MORSE.
